UNITED STATES PATENT OFFICE.

ARTHUR LAMBERT BARBER, OF HECKMONDWIKE, ENGLAND.

PAPER-RULING MACHINE.

1,068,299.

Specification of Letters Patent.

Patented July 22, 1913.

Application filed December 16, 1911. Serial No. 666,222.

To all whom it may concern:

Be it known that I, ARTHUR LAMBERT BARBER, subject of the King of Great Britain, residing at 21 George street, Heckmondwike, Yorkshire, England, have invented certain new and useful Improvements in Paper-Ruling Machines, of which the following is a specification.

This invention relates to paper ruling machines, and has reference to the construction of the slideway from which the penholders are carried, and also to the clip by which each penholder is held to the said slideway. As is well known the slideway 10 extends practically the full length of the beam and is usually made in one with the said beam, although it may be attached thereto.

An important feature of the present invention lies in adapting the clip, which is of a springy or yielding construction, to engage the outer edges of the said slideway so as to give a firmer support than is the case where spring clips are used engaging 20 grooves within the edges of, that is to say toward the center of, the slideway. I also use an inner spring clipping means in addition to the said outer clip to still more firmly support the penholders slidingly 25 upon the slideway.

Referring now to the accompanying drawings which illustrate the invention:—Figure 1 is a general view showing the slideway with a clip secured thereto and a penholder and pen in position; Fig. 2 is a cross sectional view of the slideway only; Figs. 35 3 and 4 are elevation and plan views respectively of the clip.

The slideway *a* is formed of a cross sectional shape, in which the central portion of the upper surface is hollowed or guttered as shown at *b*, leaving a small portion *c* of such surface undisturbed. At the rear part, from this upper surface it is downwardly undercut as shown at *d* (say at about 45 degrees). At the front part a slight downward beveled portion *e* is formed, and from this extends a downwardly undercut part *f* similar to that of the rear part *d*. The pen *s* is mounted on 40 a carrier *t* sliding on the penholder proper *g*.

The clip which embraces the penholder *g* has the body made from one piece of sheet metal (preferably steel). The sides *h* of each clip are carried upward and formed to 50 accommodate the pressure spring *l* for retaining the penholder *g* therein. A further

spring lever *q* may be provided for increasing the pressure of the spring *l* when the shank is in position. At the underside of this clip, and at the forward part, a tongue *m* of the metal is bent and curved into shape to suit the front part *f* of the slideway *a* aforesaid. Also at the rear part of the underside of the clip a tongue *n* of the metal is bent and shaped so as to form a spring grip 60 to engage the rear part *d* of the aforesaid slideway. These two underneath tongues may if desired be made in one piece and then secured to the underside of the main or body part of the clip, but it is an economical 70 advantage to form such tongues and body in one and the same piece.

In addition to the clip above described for gripping against the outer edges of the slideway, further spring clipping means are 75 provided at the central under part of the main clip, as shown in Figs. 1 and 3, such further clip being formed in one with, or secured to, the main clip. The additional clipping means is provided with downwardly extending front and rear portions 80 which are adapted to engage frictionally with hollowed out or guttered parts of the slideway *a*. Preferably such downwardly extending ends are of U shape, as shown at 85 *p*, each of such U members engaging with both sides of a groove *o* specially formed in the main slideway *a*.

The action of the device is as follows:— The penholder *g* is secured in the clip by 90 the upper spring pressure device *l* after the usual manner. The clip is placed upon the slideway *a*, by first passing the rear (lower) spring *n* beneath the rear undercut beveled part *d* of the slideway, when, by pushing 95 forward the clip, the forward underneath bent tongue *m* slips over the upper inclined surface *e*, and clicks under and against the undercut portion *f*. A reverse movement will of course release the clip from the slideway. The inner clipping means *p* will of course readily pass into or out of the grooves *o* during the above described operation.

What I claim as my invention and desire to secure by Letters Patent is:—

1. In a paper ruling machine, a main slideway provided with slots in the top between the edges and center thereof, and means for detachably securing a penholder slidingly on said slideway comprising a clip, 100 means for holding the penholder on said clip, spring tongues on said clip engaging

- undercut portions of the outer edges of the slideway, and means on said clip for engaging said slots.
2. In a paper ruling machine, a main slideway provided with slots in the top between the edges and center thereof, and means for detachably securing a penholder slidingly on said slideway comprising a clip, means for holding the penholder on said clip, a flat upper surface to said slideway engaging a flat lower surface on said clip, an undercut edge on one side of said slideway engaged by a spring tongue on one side of said clip, an undercut edge, having a beveled upper part, on the other side of said slideway engaged by another spring tongue on the other side of the clip, and means on said clip for engaging said slots.
3. In a paper ruling machine, a main slideway provided with slots in the top between the edges and center thereof, and means for detachably securing a penholder slidingly on said slideway comprising a clip, means for holding the penholder on said clip, spring tongues on said clip engaging undercut portions of the outer edges of the slideway, and U-shaped spring grips on said clip for engaging said slots.
4. In a paper ruling machine, a main slideway provided with slots in the top between the edges and center thereof, and means for detachably securing a penholder slidingly on said slideway comprising a clip, means for holding the penholder on said

clip, a flat upper surface to said slideway 35 engaging a flat lower surface on said clip, an undercut edge on one side of said slideway engaged by a spring tongue on one side of said clip, an undercut edge, having a beveled upper part, on the other side of said 40 slideway engaged by another spring tongue on the other side of the clip, and U-shaped spring grips on said clip for engaging said slots.

5. In a paper ruling machine, a main 45 slideway provided with slots in the top between the edges and center thereof, and means for detachably securing a penholder slidingly on said slideway comprising a clip having a flat lower surface engaging a flat 50 upper surface on said slideway, spring means for holding the penholder on said clip, an undercut edge on one side of said slideway engaged by a spring tongue on one side of the clip, an undercut edge, having a beveled 55 upper part, on the other side of said slideway engaged by another spring tongue on the other side of the clip, and U-shaped spring grips on said clip for engaging said slots.

In testimony whereof I have signed my name to this specification in the presence of two subscribing witnesses.

ARTHUR LAMBERT BARBER.
